V. DE P. SPLANE

PUMPING JAR

Filed July 18, 1922

Inventor
Vincent D. Splane

By

El. Bradford

Attorney

UNITED STATES PATENT OFFICE.

VINCENT DE PAUL SPLANE, OF PAINTSVILLE, KENTUCKY.

PUMPING JAR.

Application filed July 18, 1922. Serial No. 575,893.

To all whom it may concern:

Be it known that I, VINCENT DE PAUL SPLANE, a citizen of the United States, residing at Paintsville, in the county of Johnson and State of Kentucky, have invented certain new and useful Improvements in Pumping Jars, of which the following is a specification.

My said invention has for its purpose to provide a coupling and jarring connection between the sliding or traveling valve and the stationary valve of a pump particularly for oil wells, but adapted for any deep well, and it consists chiefly in improvements in the details of construction and arrangement of parts whereby many of the disadvantages in the use and operation of such a pump heretofore experienced are overcome and a very convenient and efficient device for the purpose provided all as will be hereinafter more fully described and claimed.

Referring to the accompanying drawings, which are made a part hereof and on which similar reference characters indicate similar parts,

Figure 1 is a sectional view through an oil pump at the point of the location of the working barrel, showing the valves and pumping jar connection between them in elevation, and in the position they occupy when the upper or sliding valve is in the position of the limit of its up-stroke, and

Figure 2 a view on an enlarged scale showing the pumping jars separately, partly in section.

In said drawings the portion marked 10 presents the working barrel of a pump, 11 and 12 sections of the pump casing, 13 the stationary valve, 14 the sliding or traveling valve, 15 the lower jar or rein, and 16 the upper jar or working rein of the connection.

The working barrel 10, the case sections 11 and 12, and the valves 13 and 14 are in the main of substantially a usual or any approved construction and arrangement. Packing rings or "cups" 20, usually of leather, are interposed between the lower edge of valve 14 and the upper edge of the socket 21 on the upper end of upper rein 16 and like cups 22 are interposed between the lower edge of the stationary valve 13 and the upper edge of a cage or crown 23. Socket 21 takes the place and serves the purpose of the crown or cage usu-

ally employed on the lower end of the sliding valve. By adjusting these crowns the packing is compressed more or less to secure the desired fit of the valves.

The pumping jars comprise two interlocked links made of steel, or material that will stand any amount of jarring service or strain without injury. The lower jar 15 is formed with a screw-threaded boss or tang 17 on its lower end adapted to screw into an internally screw-threaded collar on the upper end of stationary valve 13. The upper jar or working rein is formed with a tubular upper end on socket 21 internally screw-threaded and adapted to screw on to a screw-threaded projecting boss 24 on the lower end of the sliding or traveling valve 14. Said traveling valve 14 is attached to an operating rod 18 which is connected to the pumping jack in the usual manner. The links are formed with flat faces at 25, 26, 27, 28 and 29 which contact at the limits of the movements of the links or jars.

In assembling the parts for operation the valves are properly connected by the pumping jars 15 and 16 as shown in Figure 1 and hung to the operating rod 18 and lowered into the pump. The lower valve because of its tapered lower end readily enters the top of working barrel 10, the upper jar is lowered until its lower end meets the lower inside surface of the lower pumping jar and its upper surface meets the upper end of said lower jar making a double contact, then by a series of jarring strokes said valve 13 is driven to the lower end of the working barrel, its final position being determined by measurement or a shoulder 30, as will be readily understood. The pump is then ready for operation and operates in the usual manner, the stroke of the traveling valve 18 being varied by the length of the links and these are made of different lengths to accommodate different conditions, the ordinary or usual stroke being approximately 18 inches.

These pumping jars are made to screw directly on to the standard traveling and working valves of the type in common use, socket 21 serving the purpose of the usual crown to tighten the cups to the diameter of the working barrel. The whole is lowered into the well at one time, the lower or stationary valve being first seated, when the pump is ready for operation.

It will be understood of course that these pumping jars are designed for attachment to any valve rods or sucker rods and to be inserted in any size tube. The normal operation of the pump is not different from that commonly in use. When, however, the valve becomes "muddled up" or the working barrel filled with sand and the operation of the pump thus impaired the upper jar 10 or working rein is lowered to bring the jars together or close them. The jars are then brought together in a succession of upwardly directed jarring operations to unseat the lower valve and pull it out of the working barrel. When the lower valve is out of the barrel the fluid rushes through and washes back the sand and mud cleaning the working barrel, and then the lower valve is returned to its seat in the lower end of 15 said working barrel, as heretofore, and the pumping operation may continue. Thus this difficulty may be overcome very quickly and the necessity of pulling out the traveling valve and then lowering a grapple and 20 removing the stationary valve and then reassembling the parts, one valve at a time as has been heretofore the custom, is avoided. Another advantage in the use of 25 jars of this construction is found when it becomes necessary to pull the valves out 30 of the well as when the packing cups are cut or worn by sand. By my arrangement both the traveling and stationary valve may be removed by one operation and the 35 cups adjusted or replaced by new ones, whereas by the usual arrangement it is necessary to pull the traveling valve and remove the rods, then run the rods back into 40 the well with a grapple to pull out the standing valve.

These and other obvious advantages result from the employment of my pumping jars, all as will be readily understood.

Having thus fully described my said invention, what I claim as new and desire to secure by Letters Patent, is:

1. A pump comprising a working barrel, a stationary valve, a traveling valve and interlocked pumping jars connecting said 50 two valves, one being connected to the upper end of the stationary valve and the other to the lower end of the sliding or working valve, said pumping jars being of uniform length whereby when used for jarring pur-

poses a double contact is made at the closing of the jars, substantially as set forth. 55

2. A pump comprising a casing having a working barrel as a section thereof, a stationary valve for service in the lower end of said working barrel, a traveling valve, and pumping jars connecting said valves, the upper jar being adapted to screw on to a screw-threaded boss or collar on the lower end of the traveling valve and the lower jar being adapted to screw into a screw-threaded collar on the upper end of a lower jar, said jars being of uniform 60 length, substantially as set forth. 65

3. A pump comprising a working barrel, a stationary valve, a traveling valve, and interlocked link-like pumping jars connecting said two valves, one of said pumping jars being connected with the upper end of the stationary valve and the other with the lower end of the sliding or working valve, said valves being provided with packing and the upper valve having said packing interposed between the lower edge of the valve casing and the upper edge of a socket formed in the upper end of the upper rein of the pumping jars, substantially as set forth. 70 75

4. A pump comprising a working barrel, a stationary valve, a traveling valve, and interlocked link-like pumping jars connecting said valves one of said link-like jars being formed with a flat face for receiving a blow from the other said jar, substantially as set forth. 80 85

5. A pump comprising a working barrel, a stationary valve, a traveling valve, interlocked pumping jars connecting said two valves, one to the upper end of the stationary valve and the other to the lower end of the working valve, said jars being of uniform 90 length and formed with flat contacting faces adapted to meet at the extremes of the movements of the sliding valve, substantially as set forth. 95

In witness whereof, I have hereunto set 100 my hand and seal at Paintsville, Kentucky this 19th day of June, A. D. nineteen hundred and twenty-two.

VINCENT DE PAUL SPLANE. [L.S.]
